Robert C. Spencer, Jr.
William Franklin
McClellan & Pierce (Attys.)

UNITED STATES PATENT OFFICE.

ROBERT C. SPENCER, JR., OF RIVER FOREST, ILLINOIS, ASSIGNOR TO CASEMENT HARDWARE CO., OF CHICAGO, ILLINOIS, A CORPORATION OF ILLINOIS.

CASEMENT-WINDOW-SASH ADJUSTER.

Application filed May 31, 1922. Serial No. 564,679.

To all whom it may concern:

Be it known that I, ROBERT C. SPENCER, Jr., a citizen of the United States, and a resident of River Forest, in the county of 5 Cook and State of Illinois, have invented a certain new and useful Improvement in Casement-Window-Sash Adjusters, of which the following is a full, clear, concise, and exact description, reference being had to 10 the accompanying drawings, forming a part of this specification.

My invention relates to improvements in casement window sash adjusters, and is particularly concerned with the provision of a 15 novel type of casement window sash adjuster by means of which a casement window sash can be easily and quickly adjusted, as desired, and held in its adjusted position.

The objects of my invention are:

20 First: To provide a casement window sash adjuster comprising an arm pivotally mounted upon a portion of the window frame, means for moving the arm about its pivot point, and a slidable connection between the outer end of the arm and a member 25 secured to the sash of such construction that the arm will cause the window to open or close as it is moved in opposite directions about its pivot point.

Second: To provide a construction of the character described, in which the co-acting means at the end of the arm and on the sash comprise means for locking the arm and consequently the sash in any one of a plurality of different positions.

Third: To provide an adjuster such as described, which can be installed without notching or otherwise mutilating the screen which is interposed between the sash and 40 the operator, or requiring a stop member under the screen.

Fourth: To provide a casement window sash adjuster such as described, in which the parts secured to the window frame are 45 made flush with the surface of the window frame.

Fifth: To provide a casement window sash adjuster comprising a pivoted arm, a handle for moving said arm about its pivot point, and a fulcrum about which said arm can be tilted, the said fulcrum being so positioned relative to the arm and the handle 50 that the pressure exerted upon the handle

for tilting the arm will be effective for that purpose without causing the arm to twist, 55 and

Sixth: To provide means of the character described, which are simple in construction, economical to manufacture, and not liable to get out of order.

Other objects will appear as this description progresses, reference being had to the accompanying drawings, in which—

Figure 1 is a plan view of my improved casement window sash adjuster shown attached to the stool of a casement window frame, the frame being shown in horizontal section, and portions of our device being broken away for the purpose of better illustration. In this figure, the dotted outlines 60 show the positions of the sash and various parts of the adjuster when the sash is opened.

Figure 2 is an elevation, partly in section, of a window equipped with my device, 75 a portion of the screen of the window being broken away.

Figure 3 is an enlarged sectional detail taken on the broken section line 3—3 of Figure 1.

Figure 4 is a horizontal sectional view taken on line 4—4 of Figure 3.

Figure 5 is a vertical section taken on line 5—5 of Figure 3.

Figure 6 is a transverse section taken on line 6—6 of Figure 1, and

Figures 7, 8, 9, 10, 11 and 12 are views corresponding to Figures 1, 2, 3, 4, 5, and 6 respectively, but showing a modified embodiment of my invention.

Throughout the several views, similar reference characters will be used for referring to similar parts, and the various sections are taken looking in the direction of the small arrows.

Referring for the present to Figures 1 to 6 inclusive, the embodiment of my invention disclosed therein comprises a fulcrum plate 15, the edge of which is provided with an annular flange 16, which, together with the bottom, forms a cylindrical cup-like member having the out-turned flange 17. This cup-like member is let into an opening 18 in the stool 19 of the window frame, the flange 17 being received in a suitable countersink of 100 the opening 18. A cylindrical boss 20 projects

upwardly centrally of the plate 15, forming with the flange 16 an annular groove which receives the ring 21, having the central bore 22 for receiving the boss 20. The ring 21 is thus journaled upon the boss 20. The bore 22 tapers outwardly toward its inner end to permit the ring to be tilted upon the boss, as will be described later on.

10 Radially elongated projections 23 project downwardly or inwardly from the ring 21, there being a pair of these projections disposed upon opposite sides of the ring and in alignment with each other so as to form a fulcrum about which the ring 21 can 15 be tilted. These fulcrums bear upon the fulcrum plate 15. The ring 21 is countersunk, as shown at 24, and projecting upwardly from the bottom of this countersink are a second pair of projections 25, which are located in a vertical plane passing through the projections 23. A disk 26 is secured to the boss 20 by means of the screw 27, and forms a fulcrum plate for the projections 25.

20 Formed integrally with the ring 21 is an 25 arm which first projects upwardly a slight distance, as shown at 28, and then projects substantially in a horizontal direction, as shown at 29. The free end of this arm is 30 provided with a head 30, from the lower side of which the pin 31 projects, and in which are mounted one or more spring- 35 pressed plungers 32, which are urged outwardly by the springs 33, confined in suitable bores in the head 30, as shown in Figure 3. The head 30 slides in a channel-shaped member, which is secured to the bottom rail 34 of the sash, and comprises the bottom member 35, which is secured to the sash by screws 36, or any other suitable 40 means, and the horizontally extending flanges 37 and 37', the outer ends of which are flanged inwardly, as shown at 38, to provide means for retaining the head 30 in the channel shaped member. The lower 45 flange 37' is provided with a plurality of longitudinally spaced openings 39, adapted to receive the projecting end of the pin 31. The plungers 32 are pressed outwardly against the inner side of the flange 37, and 50 yieldingly hold the projecting end of the pin 31 in whatever opening 39 in which it happens to be positioned.

55 For the purpose of moving the arm 29 to position the sash as desired, I provide a handle comprising the bar 40, one end of which is turned at an angle thereto, as shown at 40', to be received in a socket 41 formed in the ring 21.

60 With the handle inserted as shown, when it is desired to adjust the window the operator presses downwardly upon the handle 40, thereby tilting the ring 21 on the fulcrums 23 and 25, these fulcrums being so positioned that the plane extending through them divides the angle roughly formed by

the arm 29 and the handle 40 into two parts. This causes the outer end of the arm, and consequently the head 30, to move upwardly against the tension of the springs 33, and thus releases the pin 31 from the opening 39 with which it is engaged. By then holding down upon the handle 40, and moving it about the boss 20 as an axis, the operator can cause the sash 34 to move toward either its open or closed position, as the case may be, and by then relieving the downward pressure on the handle 40, and moving it in either direction, can cause the pin 31 to come into registry with one of the openings 39 and thus lock the sash in any desired position, the spring-pressed plungers 32 causing the pin 31 to be yieldingly held in the opening 39. It will, of course, be understood that when the arm 29 is positioned as shown in full lines in Figure 1 the window will be held in its closed position.

70 It will be noticed from the above description, and from the drawings, that the tops of the flanges 17 and the top of the ring 21 are flush with the top surface of the stool 19 of the window, so that the bottom rail of the screen 42 can extend directly across the ring 21 without the necessity of cutting or notching the screen, and that, at the same time, no openings are left which will permit the entrance of bugs, flies and other insects.

75 The embodiment of my invention illustrated in Figures 7 to 12 inclusive is in all respects substantially identical with that shown in Figures 1 to 6 inclusive, except that the fulcrum plate 15' is secured to the top of the stool 19, and the boss 20 projects upwardly therefrom so that it is necessary to cut a notch 45 in the bottom rail 46 of the sash (see Figure 11) to receive the fulcrum plate, the boss and the ring 21'. In this embodiment, I have also shown the bore 22' as being tapered outwardly from the center in opposite directions to permit it to 80 be tilted about the fulcrum projections 23' and 25'. In this construction, the projections 25' are elongated more than those shown in Figure 5. In this embodiment, I have also shown the ring 21' as being provided with a projection 21'', in which a socket for receiving the handle 40 is 85 formed.

90 Otherwise, the construction of the apparatus shown in Figures 7 to 12 inclusive is substantially the same as that shown in Figures 1 to 6 inclusive, and its mode of operation is identical therewith.

95 From the above description, it will be apparent that I have provided a casement window sash adjuster of such construction that it can be easily and quickly applied to a casement window; that it can be so attached to the widow that notching or other mutilation of the screen sash is unnecessary, and 100

that with the embodiment of my invention shown in Figures 7 to 12 inclusive no openings are left between the sash and the movable parts of the adjuster, in any of its positions, sufficiently large to permit the entrance of insects, and that it is exceedingly simple in construction and economical to manufacture.

One of the features of my improved construction which is of very considerable importance is the location of the fulcrum projections on the ring, which are so positioned that when downward pressure is exerted upon the handle this pressure will be effective in lifting the outer end of the arm without the arm twisting in a direction to bind the head 30 in the channel secured to the sash, which is a fault quite common with types of casement window sash adjusters heretofore proposed.

While I have described the details of construction of the preferred embodiment of my invention, it should be clearly understood that my invention is not limited to these details, but is capable of other adaptations and modifications within the scope of the appended claims.

Having thus described my invention, what I claim is:

- 30 1. The combination with a window frame and a casement window sash hinged thereto, of an adjuster comprising a fulcrum plate let into a countersunk opening in the stool of said frame, the top of said plate being flush with the top of said stool, said plate having a flange forming a cylindrical opening, a cylindrical boss projecting centrally upwardly from said plate and spaced from said flange to form an annular groove, a ring mounted in said annular groove, an arm projecting upwardly from said ring at a point outside of the center of said ring, and then extending substantially in a horizontal direction, a channel secured to the lower rail of said casement window sash, with its flanges extending in horizontal planes, means on the outer end of said arm for making an adjustable connection with one of the flanges of said channel, a handle having one end detachably received in an opening in said ring, and projections on the top and bottom sides of said ring forming fulcrums dividing the angle between said arm and said handle, and means secured to the upper end of said boss for holding said ring in said annular opening.
- 40 2. The combination with a window frame and a casement window sash hinged thereto, of an adjuster comprising a fulcrum plate let into an opening in the stool of said frame, the top of said plate being flush with the top of said stool, said plate having a flange forming a cylindrical opening, a cylindrical boss projecting centrally upwardly from said plate and spaced from said flange to form an annular groove, a ring mounted in said annular groove, an arm projecting upwardly from said ring at a point outside of the center of said ring, and then extending substantially in a horizontal direction, a channel secured to the lower rail of said casement window sash, with its flanges extending in horizontal planes, means on the outer end of said arm for making an adjustable connection with one of the flanges of said channel, a handle having one end detachably received in an opening in said ring, and projections on the top and bottom sides of said ring forming fulcrums dividing the angle between said arm and said handle, and means secured to the upper end of said boss for holding said ring in said annular opening.
- 50 3. The combination with a window frame and a casement window sash hinged thereto, of a plate secured to the stool of said window and having a cylindrical boss extending upwardly therefrom, a ring journaled on the boss, an arm extending outwardly from said ring, a handle extending inwardly from said ring, projections on the top and bottom of said ring dividing the angle between said arm and handle, a disk secured to the upper end of said boss and co-acting with the fulcrum on the top of said ring, and a channel secured to said casement window sash with its flanges extending in a horizontal direction, and co-acting means on said arm and one of said flanges for locking said arm to said flange, and unlocking it therefrom by movement of said arm in a vertical plane.
- 60 4. The combination with a window frame and a casement window sash hinged thereto, of a plate secured to the stool of said window and having a cylindrical boss extending upwardly therefrom, a ring journaled on the boss, an arm extending outwardly from said ring, a handle extending inwardly from said ring, projections on the top and bottom of said ring dividing the angle between said arm and handle, and a channel secured to said casement window sash with its flanges extending in a horizontal direction, and co-acting means on said arm and one of said flanges for locking said arm to said flange, and unlocking it therefrom by movement of said arm in a vertical plane.
- 70 5. A casement window sash adjuster comprising a plate having an annular groove in one face thereof forming a central cylindrical boss extending therefrom, a ring in said groove journaled on said boss, said ring having projections on its top and bottom sides forming fulcrums, a disk secured to the top of said boss and co-acting with the fulcrum on the top of said ring, an arm having its inner end secured to said ring, and a handle secured to said ring and extending therefrom at an angle to said arm, said fulcrums being positioned to divide the angle between said arm and handle.
- 80 6. A casement window sash adjuster comprising a plate having an annular groove

in one face thereof forming a central cylindrical boss extending therefrom, a ring in said groove journaled on said boss, said ring having a projection on one of its sides forming a fulcrum, an arm having its inner end secured to said ring, and a handle secured to said ring and extending therefrom at an angle to said arm, said fulcrum being positioned to divide the angle between said

10 arm and handle.

7. A casement window sash adjuster comprising a plate having a central cylindrical boss extending therefrom, a ring journaled on said boss, said ring having a projection on one of its sides forming a fulcrum, an arm having its inner end secured to said ring, and a handle secured to said ring and extending therefrom at an angle to said arm, said fulcrum being positioned to divide the

20 angle between said arm and handle.

8. A casement window adjuster comprising a support, a member pivotally mounted on said support, an arm projecting from said member, and fixed fulcrum means carried by said member and co-acting with said support, said fulcrum means extending at a fixed angle to said arm.

9. A casement window adjuster comprising a support, a member pivotally mounted on said support, an arm projecting from said member, and means co-acting with said support and said member for fulcruming said member on said support to tilt about an axis extending at an angle to the pivot

35 on which said member is mounted, and at an angle to said arm, said axis being fixed with relation to said arm.

10. A casement window adjuster comprising a support, a member pivoted on said support, and an arm extending upwardly and then outwardly from said member, said

arm having means for adjustably connecting it with a casement window sash.

11. The combination with a casement window frame having a sash hinged thereto, and a screen mounted inside of said sash, of means for adjusting said sash from a position on the inner side of said screen comprising a pivot member, a ring journaled on said pivot member, the outer surface of said ring and said pivot member being flush with the outer surface of the stool of said frame, an arm extending from said ring, means secured to said sash for making a slidable connection with the outer end of said arm, and a handle secured to said ring, and extending inwardly therefrom, the lower rail of said screen passing over said ring and said pivot member.

12. The combination with a casement window frame and a sash hinged thereto, of means for adjusting said sash comprising a pivot member and a member pivoted thereon, said members being housed in an opening in the top of the stool of said frame, means extending outwardly from said pivot member for adjustably engaging said sash, and a handle extending inwardly from said pivot member.

13. The combination with a casement window frame and a sash hinged thereto, of means for adjusting said sash, said means being supported by the stool of said frame and throughout a portion of its length being flush with the top of said stool.

In witness whereof, I hereunto subscribe my name this 26th day of May, 1922.

ROBERT C. SPENCER, JR.
